O. MILLER.
COMBINATION HOT AIR HEATER.
APPLICATION FILED JUNE 8, 1917.

1,285,777.

Patented Nov. 26, 1918.

UNITED STATES PATENT OFFICE.

ORAS MILLER, OF SPENCERVILLE, OHIO.

COMBINATION HOT-AIR HEATER.

1,285,777.

Specification of Letters Patent.

Patented Nov. 26, 1918.

Application filed June 8, 1917. Serial No. 173,620.

To all whom it may concern:

Be it known that I, ORAS MILLER, a citizen of the United States of America, residing at Spencerville, in the county of Allen and 5 State of Ohio, have invented certain new and useful Improvements in Combination Hot-Air Heaters, of which the following is a specification, reference being had therein to the accompanying drawing.

10 This invention relates to a combination hot air heater, which is constructed so as to be positioned within a stove, so as to be heated to a very high degree, while air may be injected into the same, so as to be heated.

15 Another object of this invention is the production of a heating drum, which is to be positioned within the stove so as to be heated, whereby air within the drum may be heated and conveyed by the exhaust pipe 20 into the room in which the stove is placed.

A still further object of this invention is the production of a heating drum which is provided with a converging annular lower portion, so as to fit snugly upon the bowl of 25 the stove, while efficient connections are made for connecting pipes to the drum, thus, allowing air to be conducted into the drum, so as to be heated after which the air will be conveyed from the drum into the room 30 in which the stove is positioned.

With these and other objects in view this invention consists of certain novel combinations and arrangements of parts, as will be hereinafter fully described and claimed.

35 In the accompanying drawing.

Figure 1 is a vertical section through the hot air heater, taken on line 1—1, Fig. 4, and showing the stove in which the same is positioned in vertical section.

40 Fig. 2 is a horizontal section taken on the line 2—2 of Fig. 1.

Fig. 3 is an enlarged central vertical section through the heating drum, taken on line 3—3, Fig. 4.

45 Fig. 4 is an enlarged horizontal section through the heating drum.

By referring to the accompanying drawing by numerals, it will be seen that the stove comprises the usual ash pit 1, and the 50 bowl 2, and upon this bowl 2 is carried the body 3 of the stove. An ordinary draft regulator 4 may be carried by the ash pit 1, as shown clearly in Fig. 1.

The heating drum is formed in one piece

and comprises parallel side walls 5, having a 55 top 6. It will be noted that the side walls 5 are circular, one wall being of less diameter than the other, so as to be positioned at a spaced distance apart, to constitute a drum. Converging annular portions 7, are formed 60 upon the lower portion of the walls 5, and the annular bottom 8 is formed on the lower edges of these portions 7. Thus, it will be seen that an inclosed drum is formed, while the lower portion of this drum presents a 65 depending inwardly tapering annular portion. This drum is positioned within the stove so as to cause the inwardly tapering portion thereof to fit within the bowl 2, at its upper portion, as shown clearly in Fig. 70 1. In this manner the inwardly tapering portion of the drum will wedge into the upper portion of the bowl of the stove, so as to cause the drum to be held against accidental displacement or from shifting when 75 in use.

The cold air pipe 9 passes through the wall 10, so as to receive air from the outer side of the wall, if so desired, and this inlet pipe 9 has an elbow 11 provided with a nipple 12, 80 projecting through the bottom 8 of the drum, so as to communicate therewith. The internally threaded collar 13 emerges from the top 6 of the drum and the pipe 14 is threaded into engagement with this collar 13. This 85 pipe 14 also projects into the apertured top 3' of the body 3 of the stove, whereby cold air being admitted through the pipe 9 into the lower portion of the drum will be heated, and will rise so as to pass out through the pipe 14 into the room in which the stove is positioned. The auxiliary air-inlet elbow 90 15 has its upper end communicating with the interior portion of the drum, as shown clearly in Fig. 3. In this manner the air within the room will be efficiently heated, since the heated air passing from the pipe 14 will rise, while the colder air of the room will pass to a space adjacent the floor 95 of the room and will then be finally drawn into the elbow 15 and into the drum, so as to be reheated.

100 From the foregoing description it will be seen that a very efficient heating drum for a stove which has its lower portion projecting so as to fit snugly within the bowl of the stove, for holding the drum against accidental displacement, while pipes are con-

nected to the drum for injecting air there-
into, and for conveying hot air from the
drum to any position desired.

What I claim is:—

- 5 An air heater of the class described, con-
sisting of a drum comprising circular spaced
walls, a top formed upon said walls, annularly
spaced converging portions formed
upon the lower portions of said walls, an in-
10 tegral bottom formed upon said converging
portions, whereby a tapering portion is
formed upon the lower portion of said
drum, whereby said drum may be positioned

within a stove so as to wedge within the
bowl of the stove, thereby being held against 15
accidental movement, air pipes connected to
the lower portion of said drum for injecting
air thereinto, an internally threaded collar
formed upon the upper portion of said
drum, and an exhaust pipe connected to said 20
collar, whereby heated air may be conducted
from said drum.

In testimony whereof I hereunto affix my
signature.

ORAS MILLER.
